UNITED STATES PATENT OFFICE

EDWARD KANTER AND EMIL FELDMAN, OF CLEVELAND HEIGHTS, OHIO

DESIGN FOR AN ARTICLE DISPENSING STAND

Application filed February 14, 1930. Serial No. 34,557. Term of patent 14 years.

To all whom it may concern:

Be it known that we, EDWARD KANTER and EMIL FELDMAN, citizens of the United States, residing at Cleveland Heights, in the county of Cuyahoga and State of Ohio, have invented a new, original, and ornamental Design for Article Dispensing Stand, of which the following is a specification, reference being had to the accompanying drawing, forming part hereof, wherein the figure is a perspective view of the article showing our new design.

We claim:

The ornamental design for an article dispensing stand, as shown.

EDWARD KANTER.
EMIL FELDMAN.
